ARLINGTON W. STEPHENSON, OF SAN FRANCISCO, CALIFORNIA, ASSIGNOR, BY MESNE ASSIGNMENTS, TO THE FAX COMPANY, OF SAN FRANCISCO, CALIFORNIA, A CORPORATION OF CALIFORNIA

OFFSET PRINTING APPARATUS

Application filed March 30, 1931. Serial No. 526,219.

This invention relates to that form of printing known as "offset" printing in which the design on the printing plate is first printed on a rubber blanket from which the imprint 5 is "offset" to the paper.

The objects of my invention are to provide means for adapting the flat printing plate to the offset method of printing. Also such means which may be applied to a platen 10 printing press, also which will permit the use of fine screen half-tone plates for printing on coarse-grained paper with the same clear detail as in printing on high grade coated stock and without distorting the surface of 15 the paper, particularly at the edges of the plate, and also which will permit the press to give the full number of impressions per hour for which the ordinary platen printing press is designed to deliver. Other objects 20 of the invention will appear in the following description.

Before describing the apparatus, attention is called to the fact that heretofore in typographic printing a definite relation has necessarily existed between half-tone plates and the nature of the paper on which the half-tone is to be printed in order to economically produce prints having the proper qualities. A fine screen half-tone properly printed on 30 a high quality of enameled paper gives the most nearly perfect result, but if printed on a poor grade of paper, the half-tone will fill up, smut, and produce very poor results. Heretofore the 60 line and other very coarse 35 screen half-tones have been found to give the best results on newspaper stock, 85 to 100 line screen half-tones for low grade of book paper, 120 to 133 line screen half-tones for medium grade of book paper, uncoated stock 40 and lower grades of coated stock, and half-tones finer than 133 line has necessitated the use of highest grades of coated stock, while 200, 300 and 400 line screen half-tones are not ordinarily used for commercial work, but 45 are confined almost exclusively to the re-production of scientific subjects due to the slowness of production on account of the necessity for cleaning the plates at very frequent intervals.

50 With my invention fitted on a platen

press, and using a planographic plate in which the printing surface bears an image in mercury amalgamated onto the printing surface to function as a repellent for the printing ink of a roller rolled thereover, and which ink adheres to the non-amalgamated portions of the plate, 200 line screen half-tone plates produce perfect sharply defined images on any kind of paper, coated or uncoated, of any grade, soft or hard, and on 55 rough cover stock without marking the paper along the edges of the plate, so as to give a "plate sunk" effect.

In using my apparatus on a platen printing press and with the planographic plate 60 as above mentioned, more than 25,000 uniform impressions from a 200 line screen half-tone have been made on rough cover stock, high grade coated stock and newspaper stock at an average speed of 1500 impressions an 65 hour without cleaning the plate or adjusting the apparatus, without smudging the prints on any of the different papers, without loss of detail in the prints and without any noticeable wear whatsoever on the plates.

Briefly described, my apparatus comprises a flat rectangular plate herein termed "impression plate" mounted on a platen press in a manner interposed between the form and platen of the press with the opposite flat 70 faces of the plate in a plane parallel to the respective surfaces of the form and platen so that the impression plate will be squeezed between the form and the platen when the press is closed. The impression plate is covered on both sides with a rubber blanket and when the press is closed upon it the inked image on the mercury printing plate is printed on the confronting rubber-covered face of the impression plate, while at the same time 75 the opposite side of the impression plate is pressed against a piece of paper lying on the platen. The impression plate is pivotally mounted at its side edges between a pair of spaced posts or arms, so as to revolve on a 80 horizontal axis and in a manner to be carried outward from the form and the platen as the press opens after the printing operation, and means is provided to effect a 180° 85 rotation of the frame on its horizontal axis 90

55

90

95

as soon as there is sufficient clearance between the form and the platen, thereby presenting the inked impression on the rubber blanket in confronting relation to the platen for off-setting to the paper the next time the press is closed and at the same time presenting the opposite uninked side of the rubber blanket in confronting relation to the printing plate for receiving the next inked impression therefrom upon the next closing of the press.

The paper is fed to the platen in the usual manner, but with each impression the print is made on the paper from the rubber blanket at one side of the impression frame while at the same time the blanket on the opposite face of the frame receives a fresh ink impression from the printing plate, the impression plate carrying the blankets revolving 180° after each impression as stated.

While my device may be adapted to any style of platen printing press, the apparatus indicated in the drawing is shown as mounted on a platen press of the "sliding platen" type just so much of the common press elements being shown in full line as to make it clear and understandable.

In the drawings Fig. 1 is a fragmentary sectional side view of portion of a platen press showing my apparatus in place and the press open, a portion of the press being in dotted lines.

Fig. 2 is an enlarged view of my apparatus as seen from the line 2—2 of Fig. 1.

Fig. 3 is a side view of Fig. 2.

Fig. 4 is an enlarged sectional view taken along the line 4—4 of Fig. 2.

Fig. 5 is an enlarged sectional view taken along the line 5—5 of Fig. 2.

Fig. 6 is an enlarged view of a portion of Fig. 2 as seen from the line 6—6 thereof.

Fig. 7 is an enlarged sectional view taken along the line 7—7 of Fig. 2.

Fig. 8 is an enlarged sectional view taken along the line 8—8 of Fig. 2.

Fig. 9 is an enlarged detail of Fig. 1 as seen from the line 9—9 thereof.

Fig. 10 is an optional cross section of the impression plate.

In detail, 1 designates in dotted line the frame of a platen printing press of the "sliding platen" type with the platen 2 in open position for feeding, and in the closing of this press the platen is first brought to a position parallel with and then drawn against the printing plate 3 mounted on bed 4 of the press, upon operation of crank 5, this printing position of the platen being indicated in dotted line at 2' and carried out by any of a number of platen press constructions not involved in the present invention.

Ordinarily, in order to retain the paper against the platen when the platen assumes the position indicated at 2', a frisket frame 6 comprising a horizontal bar with a horizontal slot extending from end to end there-

of is pivotally mounted at its opposite ends adjacent the forward corners of the platen as at 7 and two or three upstanding parallel frisket fingers or grippers not shown, are bolted against the forward face of the frisket frame with bolts extending through the slot therein, and these frisket fingers are brought against the face of the paper to be printed on opposite sides of the plate 3 when the platen is vertical in the well understood manner, thus firmly holding the paper flat against the platen as the platen moves toward the plate 3 for making the printing impression, all of which is standard structure and well known in presses of this type.

In using my apparatus the frisket fingers are omitted from the frisket frame and a pair of vertically extending parallel bracket arms 8 are substituted therefor and are bolted at their lower ends as at 9 against the front face 80 of the frisket frame 6, best shown in Fig. 2.

Between arms 8 is mounted the impression plate 10 preferably made of aluminum, and which plate is of flat rectangular form revolvable on a horizontal axis at opposite side edges through means of outwardly extending trunnion shafts 11 journaled in the arms 8 and projecting beyond the outer sides of said arms. The shafts are provided with fixed flanges 12 secured to the edges of the impression frame by screws or otherwise.

On the projecting portions of the shafts respectively are a pair of spiral dental clutch members 13, 13'. The inner clutch member 13 is free to rotate on the shaft while the outer clutch member 13' is slidably splined on the shaft, the shaft preferably being square outward of member 13 as indicated in Fig. 5, and the member 13' having a square axial opening therethrough. The adjacent faces of clutch members 13, 13' are provided with complementary spiral ratchet teeth which are normally forced into engagement with each other by a coil spring 14 carried on the shaft outward of clutch member 13' 110 by a washer and pin as indicated.

The inner clutch member 13 carries spur gear teeth 15 around its periphery, which engage the teeth of a rack 22 slidably retained against each of the arms 8 and parallel thereto, said arms being grooved as at 16 to form guides for the racks, retaining plates 17 being secured against the arms 8 and extending over the open sides of each groove and across the outer sides of the racks to hold them in place.

The upper ends of the racks terminate adjacent the upper ends of arms 8 and are connected to each other at their upper ends by a horizontally extending rod 18, which rod 115 normally extends across the front margin of the impression plate 10 adjacent the upper edge thereof, the upper ends of arms 8 being slotted as at 19 (Fig. 6) to permit the rod 18 to pass across between the racks and to 120 130

serve as a brace or stop for the rod 18 when it is in the slot.

The guiding grooves 16 terminate above the lower ends of arms 8 and racks 22 extend 5 downward in them to a point just above the bolts 9 which secure the arms 8 to the frisket frame 6. Extending inwardly toward each other from the lower ends of the racks are short horizontal arms 20 which arms pass 10 through the lower ends of elongated vertical slots 21 in the lower ends of arms 8 respectively, the lower edges of the horizontal arms 20 resting against the lower ends of the slots. After passing through slots 21 15 the arms 20 extend vertically downward as at 20' to a point below the frisket frame and then horizontally as at 23, which latter run forms the connecting piece between the vertical runs 22, thus forming a yoke member 20, 20', and 23 connecting the two racks 22.

Midway of the run 23 of the yoke is a flat depending piece 24 formed integral with member 23 and provided with an elongated vertical slot 25.

A pair of spaced downwardly extending guide plates 26 are bolted as at 27 to the frisket frame 6, and which plates extend over the front face of the horizontal run 23 of the yoke.

In the structure described it is evident that the yoke connecting the racks 22 is free to move upward carrying the racks and rod 18 with it but is held against further downward movement by the ends of slots 21, the clutch teeth of clutches 13, 13' being arranged so that upward movement of the racks turns clutch members 13 therewith without turning clutch members 13', but latter clutch members engage with members 13 for turning on a downward movement of the racks only, and turn the impression frame 10 completely over.

In order to automatically effect an upward movement of the yoke and racks when the press opens, a pair of stationary cams 28 with horizontal upper surfaces are bolted to opposite sides of the press frame 1 in the lower end of a cut out portion provided 45 in the press frame for permitting free movement of the platen and frisket frame into the vertical printing position as indicated in dotted lines at 2' in Fig. 1.

When the frisket frame, carrying the complete structure, as already described moves with the platen to assume the position indicated at 2' in Fig. 1, the lower edges of the outer ends of the horizontal run 23 of the yoke engage against the horizontal upper faces of cams 28 before the extreme downward movement of the frisket frame is reached, and as the action of the press continues to move the frisket frame downward, the yoke and mechanisms secured thereto are forced upward so that the rod 18 connecting

the upper ends of the racks is clear of the upper edge of the revolvable plate 10 as at 18' in Fig. 2. Upon a subsequent downward movement of the yoke, it is evident from the structure already described that the spiral or ratchet clutches 13, 13' will engage and effect a 180° revolution of impression plate 10 and the rod 18 will be lowered into its position in front of the upper margin of plate 10.

Means is provided for lowering the rack bars and yoke, and this comprises a pair of coil tension springs 29 positioned adjacent the front faces of arms 8 respectively, the upper ends of the springs being secured to rod 18 at their upper ends and at their lower ends each to the arms 8 respectively as and at best indicated in Fig. 2.

In order to retain the impression plate 10 against turning until the platen and form are sufficiently separated, a pair of leaf springs 30 are secured at 30' at their lower ends by bolts or rivets to the rear face of the vertical run 22 of the yoke and extend upward so as to slide over the rear face of plate 10 adjacent its side edges when the yoke is forced upward upon the closing action of the press as described.

Additional means is also provided for holding the plate 10 between the arms 8 until 95 released by the force of springs 29 comprising a pair of inwardly urged friction catches 31 each projecting inwardly from arms 8 and with their inner ends adapted to seat in suitable recesses in the side edges each of impression plate 10 adjacent the lower corners of the plate.

In the normal action of the press by the time the platen has moved away from the bed and form a sufficient distance to enable a free 105 180° revolution of the frame 10, the yoke will have been pulled down by springs 29 sufficiently far to permit plate 10 to be released from leaf springs 30 by overcoming the resistance of the leaf springs, and will quickly effect a half turn of the plate which turn is limited by rod 18 which automatically descends into the slots in the upper ends of arms 8 respectively in front of the plate and in which position further revolution of 110 plate 10 is impossible.

The catches 31 in the sides of arms 8 adjacent the lower corners of the plate also function to retain the plate 10 against rebounding out of position between arms 8 120 after the half revolution of the plate is completed, as the plate would otherwise have a tendency to do upon striking rod 18 along its upper margin.

In view of the positive and powerful action of a platen press, it is essential to also provide means positively actuated by the movement of the press itself, instead of placing full reliance on coil springs 29, to turn the plate 10, as serious damage to the device 125 130

and press might result were the plate 10 not to make a full half turn and to this end a strap iron bracket 32 is bolted at one end to cross brace 33 of the press frame, which

5 brace or similar member found in most presses of this character extends between the sides of the press beneath the platen carriage. Bracket 32 extends inward towards the bed of the press and is provided with a bearing 10 32' at its inner end in which is mounted a short shaft 34 extending horizontally and transversely of the bracket. Shaft 34 carries at one end an upwardly extending hook 35 which has a straight downwardly extending 15 shank 36, the shank extending through the shaft and a distance below it. A pair of collars are pinned to the shaft 34 on opposite sides of the bearing 32 as indicated in Fig. 9 to prevent longitudinal displacement of the 20 shaft, yet to permit it to freely rotate therein.

Around the shaft and between the bearing 32' and the hook 35 I provide a torsion spring 37, one end of which bears against the bracket and the opposite end against the hook 35 and 25 is adapted to force the hook in a direction away from the press bed. Opposing the force of spring 37 is a coil tension spring 38 secured at one end to the end of shank 36 and to the other end of the spring is attached the 30 end of a small cable 39 the other end of the cable being secured by a bolt to the longitudinally extending "throw off" arm 40 of the platen carriage as indicated in Fig. 1.

In operation, when the platen carriage has 35 moved away from the bed of the press a sufficient distance to enable the frame 10 to turn, and just after the frame has turned, hook 35 is pulled forward against the force of torsion spring 37 under the superior force of 40 spring 38 and enters slot 25 of piece 24 of the yoke and engages the piece 25 at the lower end of the slot, and as the platen continues to recede from the bed, raising the yoke, the yoke member and racks secured 45 thereto are positively pulled downward to forcibly complete the half turn of plate 10 should the springs 29 fail for any reason to carry out their function. In the reverse motion of the platen, namely, toward the press 50 bed, the tension on spring 38 is relieved and the hook moves out of slot 25 to dotted position 35' in Fig. 1, so as to permit the yoke to descend to its full downward limit for resetting the clutch members for a succeeding 55 turn of plate 10. The use of springs 29 to turn the plate 10 is preferable to effect a uniform turning of the plate, since it is obvious that were the hook 35 depended upon to perform the full function of turning the plate, 60 the turning force would vary with the speed of the press, at times not effecting as rapid an action as would be desired and at other times the force would be stronger than desired and cause excessive wear on the parts. 65 The hook 35 merely provides extra or dual

means for insuring a complete turn of the impression plate, although it would operate alone without the springs 29.

Hook 35 is adjustable in its motion by tightening or releasing the tension of spring 70 38.

The impression plate 10 of my device is recessed on its opposite flat faces as best shown in Fig. 4, the face of the margin of the plate around the recesses being flush with the rear 75 faces of arms 8 irrespective of which face of the plate is turned to face the rear side.

Preparatory to printing by use of my device, a filler or pad comprising several cards 80 42 of coated stock and a blotter or several blotters 43 are first placed in the recesses in the plate faces in which the filler is adapted to snugly fit with the cards 42 at the bottom of the recess and the blotter on top, the blotter extending above the face of the margin 85 of the plate. Preferably the pad or filler is gummed along an edge to prevent the cards and blotters shifting relative to each other and to make a unitary filler of different paper stock. 90

With the fillers in place, one in each recess on opposite sides of the impression plate, a firm countersunk impression of the printing plate is made in each of the fillers by closing the press to printing position with the printing plate 3 (on its block 3') locked in the chase 4' on the bed 4 of the press. After making these impressions which leave countersunk depressions in the fillers the size of the printing plate, a piece of hand-coated 100 cardboard 44 or a piece of stencil board of slightly smaller dimensions than the printing plate is placed in each of the depressions made in the filler, leaving a free or open margin 48 between the edges of the board 44 and the edge of the depression made by the printing plate A the face of the board being above the face of the blotter. The frame 10 with its fillers prepared as described are then removed from between the arms 8 by turning the plate 10 to the dotted position 10' in Fig. 1 in which position the screws mounting the shafts 11 to the plate are exposed and are easily removed. An endless resilient rubber blanket 45 is then slipped over one end of the plate 10, fillers, and boards 44, so as to leave the side margins of the plate free for leaf springs 30 to slide thereagainst as already described. With the blanket in place 110 the fillers and boards 44 are firmly held in place by friction. 115

The plate 10 with the filler and blanket in place forms a unit which is then remounted on bearings 11 and is ready for receiving 120 inked impressions on the rubber blanket from the printing plate for offsetting to the paper.

However, it is preferable to also cover the platen with a resilient rubber blanket as indicated at 46, on which is laid the paper to 125

receive the offset impression from the blanket 45 on the rear side of plate 10.

It is important to note that the process of forming the depressions in the fillers and inserting the card 44 therein to raise the portion of the filler to receive the inked impression from the plate, eliminates the necessity for underlaying the back of the printing plate to insure an evenly inked impression, and also prevents the edges of the printing plate from cutting into the rubber blanket during the printing operation, since the edges of the plate overhang the edges of the card 44, as best indicated in dotted line in Fig. 4 and they are therefore entirely relieved of pressure.

Instead of making the impression plate as shown in Fig. 4 wherein it is a built-up series of members with a central sheet or web 10" of metal, the whole thing may consist of a light metal open frame holding a series of padding sheets as shown in Fig. 10 wherein the margins of the "plate" are made of two overlapping thin metal angle strips 49, 50 held together as by screws 51, the outer strips being provided with lugs 52 carrying the pivot shafts 53 on which the whole "impression plate" revolves. Within the frame are layers of padding or pressure receiving material comprising a central sheet of heavy stencil board 54 on opposite sides of which are sheets of firm rubber 55 preferably reinforced with duck, then comes thin stencil board 56, then sheets of coated cardboard stock 57, then relief padding 58 of thin cardboard, and finally the offset rubber blanket 45 which wraps around the whole assembly as described for Fig. 4 to thus form my "impression plate", though it really has a yielding center.

This compound impression plate is more yielding than the plate of Fig. 4, though if in the latter figure the web 10" be very thin or not made integral with the outer frame 10 it is about the same, though in some respects I find the floating or yielding center type of impression plate to work best.

From the above it will be seen that my use of the words "impression plate" is to be construed broadly as covering any modifications, whether flexible, rigid, built-up or otherwise.

In making the printing plates for printing by my process and with the device described, the area on the plate carrying the image is as indicated at 47 in Fig. 4, the extreme edges of the plate and margin being left blank and covered with mercury to repel the ink.

It is obvious to anyone skilled in the art that certain parts of my device may be changed according to the nature of the press on which it is used. It is also obvious that it may be used in printing ordinary half-tone plates, or other cuts, as it is not limited to use with mercury planographic plates, but it consists broadly in an automatic reversal apparatus for carrying out offset printing from flat forms on platen presses of any descrip-

tion, and any modifications or use falling within the spirit of the invention are intended to be covered in my appended claims.

I claim:—

1. In combination with a platen type of printing press, a flat offset impression plate positioned between the printing form and the press platen, means mounting said impression plate for revolution to present opposite sides in succession to the form and the platen, and dual means operated in synchrony with the press movements for revolving the plate a half turn between impressions, one of said dual means being resiliently operated and the other positively operated, the latter arranged to take effect upon failure of the former.

2. In combination with a platen type of printing press, an offset impression plate positioned between the printing form and the press platen, means mounting said impression plate for revolution to present opposite sides in succession to the form and the platen, the means mounting said impression plate including an attachment whereby it is wholly supported from the frisket frame of the press, and means operated in synchrony with the press movements for revolving the plate between impressions.

3. In combination with a platen type of printing press, an offset impression plate positioned between the printing form and the press platen, means mounting said impression plate for revolution to present opposite sides in succession to the form and the platen, and means operated in synchrony with the press movements for revolving the plate between impressions, the means mounting the impression plate comprising a pair of vertically positioned supporting arms, horizontal pivots between the plate and arms whereby the plate may be revolved between the arms, and the means for revolving the plate comprising resilient power means for urging the plate to revolve on its pivot, stop means limiting the revolution of the plate, and means for intermittently actuating said resilient power means.

4. In combination with a platen type of printing press, an offset impression plate positioned between the printing form and the press platen, means mounting said impression plate for revolution to present opposite sides in succession to the form and the platen, and means operated in synchrony with the press movements for revolving the plate between impressions, the means mounting the impression plate comprising a pair of vertically positioned supporting arms, horizontal pivots between the plate and arms whereby the plate may be revolved between the arms, the means for revolving the plate comprising springs for urging the plate to revolve, movable stop means limiting the revolution of the plate, and means actuated by

the press movements intermittently actuating said springs and moving said stop means.

5. Offset printing apparatus comprising a flat offset impression plate, supports at opposite edges of said plate, means pivoting the plate to the supports for revolution of the plate, a revolvable clutch associated with one of the pivots, a rack bar slidably supported on one of said supports engaging said 10 clutch, a spring arranged for sliding the rack bar, and means for tensioning the spring to cause revolution of said clutch and plate.

6. Offset printing apparatus comprising a flat offset impression plate, supports at opposite edges of said plate, means pivoting the plate to the supports for revolution of the plate, a revolvable clutch associated with one of the pivots, a rack bar slidably supported on one of said supports engaging said 15 clutch, a spring arranged for sliding the rack bar, means for tensioning the spring to cause revolution of said clutch and plate, and means for stopping said plate at each half turn.

25 7. In printing apparatus of the character described, a flat impression plate provided on opposite sides with a flexible sheet rubber blanket formed in an endless band tensioned around the plate.

30 8. In printing apparatus of the character described, a flat impression plate provided on opposite sides with a flexible sheet rubber blanket and padding under the blanket arranged to register with, but of lesser size 35 than the printing form.
